UNITED STATES PATENT OFFICE.

DOMINICK ANTHONY ROMEO, OF NEW ORLEANS, LOUISIANA, ASSIGNOR TO SIMON J. SCHWARTZ, JR., OF NEW ORLEANS, LOUISIANA.

TROUSERS-CARTON.

1,320,575.

Specification of Letters Patent.

Patented Nov. 4, 1919.

Application filed June 2, 1919. Serial No. 301,237.

To all whom it may concern:

Be it known that I, DOMINICK ANTHONY ROMEO, a citizen of the United States of America, residing at New Orleans, in the parish of Orleans and State of Louisiana, have invented certain new and useful Improvements in Trouzers-Cartons, of which the following is a specification.

The primary object of the present invention is to provide a carton for carrying or transporting garments, more particularly trousers in which the trousers may be so arranged therein as to retain the original pressing without being wrinkled due to folding and wherein the carton is peculiarly constructed to permit the legs of the trousers to be folded with the folded portions thereof spaced apart to prevent a flat creasing at that point.

With this and other objects in view, the invention consists in the novel form, combination and arrangement of parts herein-after fully described and shown in the accompanying drawing, in which like reference characters indicate similar parts throughout the several views.

In the drawing,

Figure 1 is a plan view of an unfolded carton constructed in accordance with the present invention,

Fig. 2 is a plan view of the carton with a pair of trousers shown in dotted line position and folded therein with the blank remaining open,

Fig. 3 is a vertical cross sectional view taken on line III-III of Fig. 2 showing the relation of the side flaps and the main section, and

Fig. 4 is a detail perspective view of the trousers supporting section of the carton with the other section partially broken away.

Referring more in detail to the accompanying drawing, there is provided a blank embodying two sections, 5 and 6 respectively, divided by a central scored line 7 into sections of substantially equal areas. The section 5 forms the cover of the carton and carries an end flap 8 formed by a scored line 9 and side flaps 10 formed by scored lines 11, the adjacent corners of the flaps 8 and 10 being cut away as illustrated to facilitate folding of the flaps as will be obvious.

The trousers supporting section 6 is provided with a pair of identically formed side

flaps 12 extending from the scored line 13. At points spaced inwardly of the side edges of the section 6, the scored line 13 is cut through to provide a slot 14 at each side of the section 6 and with the transverse end 60 cuts 15 in the flaps 13, there is provided upper and lower extensions 16 and 17. As shown more clearly in Figs. 3 and 4, the upper extension 16 is bent to a substantially curved position to provide a rounded edge at 65 the folded portion of the end flap while the lower extension 17 is more abrupt and supports the wider portion of the trousers legs.

When it is desired to place the trousers 70 A, shown in dotted lines in Fig. 2, in the carton, the blank shown in Fig. 1 is employed and the side flaps 12 bent at the scored lines 13 with the subsequent bending of the extensions 16 and 17 of the flaps 12 75 to the positions shown in Fig. 3 to clear the slotted openings 14 as illustrated. The lower portion of the trousers, after having been properly folded in their creased lengthwise position, is passed through the slot adjacent the extension 17 and drawn downwardly therethrough until the waist portion of the trousers is properly positioned upon the section 6 as shown in Fig. 2, at which time, the legs of the trousers are folded upon 80 themselves and over the extension 17 and lower flap 12 to be passed through the upper part 14 adjacent the extension 16, drawn taut and subsequently folded over the curved extension 16 to the position shown in Fig. 90 2. With the trousers so arranged, the folded portions thereof are prevented from becoming creased and are held separated by the extensions 16 and 17 as well as the angular disposition of the side flaps 12. The carton 95 is then folded upon the scored line 7 with the end and side flaps 8 and 10 folded upon the scored lines 9 and 11 about the rear face of the section 6 and when so arranged the carton may be secured in any preferred 100 manner as by tying the same with cord or securing the same with pasters.

It is to be understood that the present carton may be made out of any preferred material as heavy paper, cardboard, strawboard or any stout material desired, the gist of the invention residing in the association of the side flaps 12 with the section 6 and the slots formed in the side flaps, and while there is shown the preferred embodiment 110

of the invention, it is nevertheless to be understood that various changes may be made as will fall within the scope of the invention as claimed.

5. What I claim as new is:—

- 10 1. A garment carton formed of a rectangular blank, a scored line substantially midway the ends thereof dividing the same into two substantially equal sections, end and side flaps carried by one section, and side flaps carried by the other section, the side flaps of the last named section being slotted.
- 15 2. A garment carton formed of a rectangular blank, a scored line substantially midway the ends thereof dividing the same into two substantially equal sections, end and side flaps carried by one section, and side flaps carried by the other section, the side flaps of the last named section being slotted, the wall of the side flaps adjacent the slots projecting outwardly therefrom to
- 20 present a substantially curved end at the slotted portion.

3. A garment carton formed of a blank having a scored line substantially dividing the same into equal sections, end and side flaps carried by one section, side flaps carried by the other section, the last named side flaps adapted to be folded inwardly, and having slots therein, an inward extension carried by the side flaps at the edges of the slots, and adapted to lie inwardly of the other section when the blank is folded on the main scored line, and with the first named end and side flaps bent about the last named section.

4. A trousers carton formed of a blank divided into two substantially equal sections, side and end flaps carried by the sections, and trousers receiving slots provided in opposite flaps of one section with the cut away portions of the flaps adjacent the slots affording separating elements for the folded portions of the trousers.

In testimony whereof I affix my signature.
DOMINICK ANTHONY ROMEO.
